UNITED STATES PATENT OFFICE.

DEVILLO PALMER, OF DETROIT, MICHIGAN.

CAMERA ATTACHMENT.

1,209,015.

Specification of Letters Patent. Patented Dec. 19, 1916.

Application filed July 7, 1915. Serial No. 38,574.

To all whom it may concern:

Be it known that I, DEVILLO PALMER, a citizen of the United States, residing at Detroit, in the county of Wayne and State of Michigan, have invented new and useful Improvements in Camera Attachments, of which the following is a specification.

This invention relates to cameras, and similar photographic apparatus and more particularly to novel means for holding the shutter operating lever against accidental operation.

In cameras and similar devices employing a shiftable lever for actuating the shutter it is frequently found that two pictures are taken upon the same film through the accidental shifting of the lever.

It is, therefore, the object of this invention to avoid this difficulty, and broadly speaking, the invention consists in providing a simple and efficient lock for locking the lever in either position so that it cannot be moved accidentally.

Further objects of the invention will appear as the following specific description is read in connection with the accompanying drawing which forms a part of this application, and in which:

Figure 1 is an elevation showing the lock attached to a camera and showing in full lines the position of the lock in operative position and in dotted lines in inoperative position. Fig. 2 is a sectional view taken on the line 2—2 of Fig. 1.

Referring more particularly to the drawing, 1 represents the casing of the camera, 2 the shutter and 3 the shutter operating lever.

Mounted upon the casing and provided with a slot to receive the shutter operating lever 3 is a mounting plate 4 having struck up therefrom a catch 5 immediately above which is positioned a laterally projecting locking pin 6. Pivoted to the mounting plate 4 is a resilient locking bar 7 having a laterally projecting lug 8 forming spaced shoulders arranged to engage upon opposite sides of the shutter operating lever 3. When the bar 7 is thrown to the position shown in full lines in Fig. 1, it will be elevated by the inclined catch 5 which will cause the pin 6 to enter the aperture 9 in the end of the lever when the latter springs back against the plate 4 at the opposite side of the catch 5 and thus lock the same in opera-

tive position. If the lever 3 is in the upper portion of the slot of the mounting plate, its under side will be engaged with the upper shoulder of the lock 8 while if the lever 3 is in the lowermost part of the slot, its upper side will be engaged with the lower shoulder of the lock 8. The bar 7 has its free end preferably provided with a laterally extending lug or finger holds 10 by which the same may be manipulated.

What is claimed is:

1. Means for locking the shutter shifting lever of cameras comprising a slotted mounting plate arranged to receive the shifting lever, a bar pivoted to the mounting plate and having a laterally extending lug adapted to alternately engage the opposite sides of the shifting lever, said bar being resilient, means for locking the bar in operative position, and means for moving the upper end of the bar away from the said plate when drawn into operative position to engage said locking means.

2. Means for locking the shutter shifting lever of cameras, comprising a slotted mounting plate arranged to receive the shifting lever, a resilient bar pivoted to the mounting plate, and having a laterally extending lug adapted to alternately engage the opposite sides of the shifting lever, means for locking said lever in its operative position, and an obstructing element disposed in the path of movement of said bar to move the latter away from the plate when drawn into operative position, to engage said locking means.

3. Means for locking the shutter shifting lever of cameras, comprising a slotted mounting plate arranged to receive the shifting lever, a bar pivoted to the mounting plate and having a laterally extending lug arranged to alternately engage the opposite sides of the lever, said bar being resilient, and a pin projecting from said plate and adapted to be received within an opening in said bar for holding the latter in operative position.

4. Means for locking a shutter shifting lever of cameras, comprising a slotted mounting plate arranged to receive the shifting lever, a bar pivoted to the mounting plate and having a laterally extending lug adapted to alternately engage the opposite sides of the shifting lever, said bar being resilient, a pin projecting from said plate

and adapted to be received within an opening in said bar when the latter is in operative position, and means for moving the upper end of the bar away from the plate to receive said pin, when said bar is thrown into operative position.

In testimony whereof I affix my signature in presence of two witnesses.

DEVILLO PALMER.
